[57] **CLAIM**

The ornamental design for a side element of a shoe upper, as shown and described.

DESCRIPTION

FIG. 1 is a side elevational view of a side element of a shoe upper showing my new design;
FIG. 2 is a front elevational view thereof;
FIG. 3 is a rear elevational view thereof;
FIG. 4 is a top plan view thereof; and,
FIG. 5 is a side elevational view of the side element of a shoe upper shown in FIG. 1, with the broken line showing of the zig-zag ornamentation being removed for clarity.
The broken line showing of a shoe sole and the remaining portion of the upper shown in FIGS. 1-5, the broken line showing of the lace loops in FIGS. 1 and 5, and the broken line showing of the zig-zag ornamentation in FIG. 5 are for illustrative purposes only and form no part of the claimed design.
